BOBBIN CLUTCH

Richard C. Hare, Grafton, Mass., assignor to
Whitin Machine Works, Whitinsville, Mass., a
corporation of Massachusetts

Application October 9, 1946, Serial No. 702,271

1 Claim. (Cl. 242—46.6)

1

This invention relates to spindles used on spinning or twisting machines, and more particularly to clutches for driving bobbins mounted on such spindles.

It has been heretofore customary to provide a bobbin clutch for such purposes in which a plurality of spring fingers were loosely mounted within a slotted bushing or shell and pressed outwardly to engage and drive the bobbin, the driving pressure of the fingers being increased by centrifugal force when the spindle was rapidly rotated. The driving whirl on the spindle was sometimes displaced downwardly when a fresh bobbin was too forcibly applied, thus separating the whirl from the slotted bushing and allowing the clutch parts to separate and to admit dust or lint.

It is the general object of my present invention to provide an improved bushing construction by which the objection above noted is effectively avoided.

More specifically, I provide a unit construction in which the spring finger assembly is positively and permanently secured within the slotted bushing and is supported on the spindle entirely independent of the driving whirl.

My invention further relates to arrangements and combinations of parts which will be hereinafter described and more particularly pointed out in the appended claim.

Preferred forms of the invention are shown in the drawings, in which

Fig. 1 is a partial side elevation of a spindle with my improved bobbin clutch shown in section along the line 1—1 in Fig. 2;

Fig. 2 is a plan view of the parts shown in Fig. 1;

Fig. 3 is a sectional front elevation of the slotted bushing, taken along the line 3—3 in Fig. 2;

Fig. 4 is a side elevation of the spring finger assembly; and

Fig. 5 is an enlarged partial sectional view of certain parts shown in Fig. 1.

Referring to Fig. 1, I have shown a spindle blade 10 having a driving whirl 11 forced thereon, and I have shown my improved bobbin clutch as comprising a bushing 12 and a plurality of spring fingers 14. The spring fingers 14 are preferably formed as a one-piece spring finger assembly, as shown in Fig. 4, with the lower ends of the spring fingers 14 joined by connecting portions 15.

The bushing 12 (Fig. 3) comprises a cap or head portion 20, a plurality of depending portions 21 separated by slots 22, and a continuous annular bottom flange 25 to which the lower ends of all of the portions 21 are secured. Preferably, the entire bushing 12 is formed as a single piece of material.

After the bushing and spring fingers are assembled, the inner bottom edge of the bottom flange 25 of the bushing 12 is rolled or swaged

2

as indicated at 31 in Fig. 5 to hold these parts assembled with the top edge 15a of the connecting portion 15 engaging the lower ends 21a of the depending portions 21 of the bushing 12. The connecting portion 15 of the spring finger assembly is thus securely anchored to the bushing 12.

The bottom flange 25 of the bushing 12 is received in a recess 30 in the upper end of the whirl 11 but is preferably a loose fit therein, while the head 12 is a drive fit on the blade 10.

The slotted bushing 12 and the spring fingers 14 thus form a permanently assembled bobbin-driving unit which is separately mounted on the spindle blade 10 and which remains thus assembled even if the spindle whirl is downwardly displaced. The unit construction also facilitates spindle assembly and holds the spring assembly more positively in the desired position on the spindle blade.

Having thus described my invention and the advantages thereof, I do not wish to be limited to the details herein disclosed, otherwise than as set forth in the claim, but what I claim is:

25 In a spindle having a blade and a driving whirl mounted thereon, a bobbin clutch comprising a one-piece bushing having a head fixed on said blade and a continuous annular bottom flange positioned adjacent the upper part of said driving whirl but free therefrom and having a slotted body portion connecting said head and flange, and a separate spring finger assembly comprising an annular bottom flange enclosed by the bottom flange of said bushing and a plurality of spring fingers extending freely upward from said bottom flange and positioned in the slots of said body portion, and the lower inner corner portion of said bottom bushing flange being inwardly displaced to secure said bushing and said spring finger assembly together to form a permanent unit and to prevent longitudinal displacement of said spring fingers relative to said bushing.

RICHARD C. HARE.
